COMBINATION BOTTLE OPENER

Lorraine E. Haverkost, Overland, Mo.

Application May 16, 1949, Serial No. 2,685

Term of patent 14 years

(Cl. D44—29)

To all whom it may concern:

Be it known that I, Lorraine E. Haverkost, a citizen of the United States, residing at #3462 St. Williams Lane, in the city of Overland, county of St. Louis, and State of Missouri, have invented a new, original, and ornamental Design for a Combination Bottle Opener, of which the following is a specification, reference being had to the accompanying drawing, forming part thereof.

In the drawing

Fig. 1 is a bottom plan view of the combination bottle opener, showing my new design;

Fig. 2 is a top plan view of the same.

Fig. 3 is a side elevational view of the same, showing the cork screw thereof opened out for use, and the two handles closed.

Fig. 4 is a side elevational view of the same, showing the cork screw thereof closed, and the two handles opened out for use.

I claim:

The ornamental design for a combination bottle opener, as shown and described.

LORRAINE E. HAVERKOST.
